[57] CLAIM

The ornamental design for a clock, substantially as shown and described.

DESCRIPTION

FIG. 1 is a right front perspective view of a clock showing my new design with the door in a closed position; FIG. 2 is a right front perspective view thereof with the door in an opened position;

FIG. 3 is a top plan view thereof, the bottom being flat, plain and unornamented;

FIG. 4 is a right side elevational view thereof, the left side being a mirror image thereto;

FIG. 5 is a rear elevational view thereof;

FIG. 6 is an enlarged sectional view of the clock dial as seen in FIG. 2.
